(57) **CLAIM**

The ornamental design for a rosin bag, as shown and described.

DESCRIPTION

FIG. 1 is a front view of a rosin bag showing my new design; FIG. 2 is a rear view of the rosin bag; FIG. 3 is a left side view of the rosin bag; FIG. 4 is a right side view of the rosin bag; FIG. 5 is a top view of the rosin bag; FIG. 6 is a bottom view of the rosin bag; and, FIG. 7 is a top front side perspective view of the rosin bag. The dot-dot-dash lines depict portions of the rosin bag that form no part of the claimed design.
